CLAIM

The ornamental design for a 3-D design element for hardware, as shown and described.

DESCRIPTION

The patent or application file contains at least one drawing executed in color. Copies of this patent or patent application publication with color drawing(s) will be provided by the Office upon request and payment of the necessary fee.

FIG. 1 is a color perspective view of the 3-D design element for hardware with surface pattern;

FIG. 2 is a color front view of the 3-D design element for hardware with surface pattern of FIG. 11;

FIG. 3 is a color bottom side view of the 3-D design element for hardware with surface pattern of FIG. 11, with the opposite top side being a mirror image thereof;

FIG. 4 is a color right side view of the 3-D design element for hardware with surface pattern of FIG. 11, with the left side being of identical appearance; and,

FIG. 5 is a rear back side view of the 3-D design element for hardware with surface pattern of FIG. 11.
